UNITED STATES PATENT OFFICE.

JOHN W. VANAMBURGH, OF HORSEHEADS, NEW YORK.

DESIGN FOR A COMBINED JARDINIÈRE-STAND AND TREE-SUPPORT.

47,766.

Specification for Design.

Patented Aug. 24, 1915.

Application filed May 17, 1915. Serial No. 28,767. Term of patent 7 years.

To all whom it may concern:

Be it known that I, JOHN W. VANAMBURGH, a citizen of the United States, residing at Horseheads, in the county of Chemung and State of New York, have invented a new, original, and ornamental Design for a Combined Jardinière-Stand and Tree-Support, of which the following is a specification, reference being had to the accompanying drawings, forming part thereof.

The figure is a perspective view of my improved stand and tree support.

This stand consists of the three supporting legs having the ornamental configuration shown and the upper and lower annular

supporting members disposed intermediate and connected to said legs, to receive a jardinière or other similar article. The supports are also provided with registering openings to receive the base of the tree as clearly shown by the drawings.

I claim:

The ornamental design for a combination jardinière stand and tree support as shown and described.

JOHN W. VANAMBURGH.
